PAUL KLEMM, OF GAUTZSCH, AND LOUIS SCHOPPER, OF LEIPZIG, GERMANY.

APPARATUS FOR TESTING PAPER-PULP.

No. 910,002.

Specification of Letters Patent.

Patented Jan. 19, 1909.

Application filed February 28, 1908. Serial No. 418,381.

To all whom it may concern:

Be it known that we, PAUL KLEMM and LOUIS SCHOPPER, subjects of the German Emperor, residing at Gautzsch and Leipzig, respectively, both in the German Empire, have invented certain new and useful Improvements in Apparatus for Testing Paper-Pulp, of which the following is a specification.

10 This invention relates to apparatus for testing paper pulp.

Accurate determination of the quality and nature of paper pulp is of the highest importance to the dealer and manufacturer. 15 On the one hand it is essential to ascertain whether the pulp is suitable for the manufacture of the particular kind of paper required. On the other hand the pulp must be tested in the course of its treatment to 20 accurately ascertain when it has reached the conditions suitable for the purpose in view. For performing these tests the manufacturer or foreman has hitherto been compelled to rely on the sensitiveness of his touch, and 25 the accuracy of his judgment. The success of the process was thus largely dependent on expert skill. In important cases it was necessary to make samples of paper, and subject the same to the usual tearing and 30 bending tests.

The present invention is based on the fact that the volume of wet paper pulp or pulp mixtures, after the separation of such amount of water as will drain naturally 35 therefrom, is directly related to the fineness and nature of the pulp. For example, in the case of material having long fibers, which is carefully treated with blunt knives in the rag-engine, the volume of the pulp 40 after drainage is small, notwithstanding the length of the fibers, and the pulp is suitable for the manufacture of the finer and stronger qualities of paper. The pulp is "greasy." If the material is treated with sharp knives 45 the pulp produced is rough, even if the rags were finely divided, and the volume after drainage is larger. The degree of plasticity and fineness can thus be reliably ascertained

by simply draining the water from the pulp and observing the remaining volume, and 50 numerical coefficients may be determined to guide the manufacturer in ascertaining the nature and quality of the paper which can be produced from any particular pulp.

Apparatus suitable for the purposes of 55 the volumetric tests described is illustrated in the annexed drawing, in which—

Figure 1 is a side view, partly in section, Fig. 2 a front view, and Fig. 3 a cross-section on line 3—3 of Fig. 1.

The apparatus comprises a glass tube *a* carried by a clamp *b* fixed to an axle *d* which is rotatable in a hole in a pillar *d'*. A crank handle *g* fixed to the axle allows of 60 uniformly mixing pulp and water therein. A spirit level may be provided to indicate when the latter is exactly vertical, and marks may be made on the axle and pillar to enable a corresponding adjustment of the 65 tube *a* to be obtained. The one end of the tube is closed by a removable cap *i* on which is mounted a cock *h*. The other end of the tube there is a sieve *k* and a lid *n* which is hinged at *m* and adapted to be held in its 70 closed position by a spring catch *p*. A scale is marked on the front of the tube.

Tests can be made in various ways. The most convenient method is to place a pre-determined quantity of dry pulp, for example one gram in the tube *a*, and fill the tube *a* with water up to the 100 c. m. mark. This forms a one per cent. mixture. The cap *i* is then replaced, with the cock *h* closed. The tube is then rocked to uniformly saturate and distribute the pulp in the water. Thereupon the tube is adjusted in its vertical position, and the cock *h* and lid *n* are opened, so that the water can drain through the sieve *k*. The volume of wet pulp remaining 80 on the sieve after the water has ceased to flow out is then ascertained by means of the scale on the tube, and affords an indication of the quality of paper which can be produced from the pulp.

What we claim as our invention and de-

sire to secure by Letters Patent of the
United States is:—

Apparatus for testing paper pulp, com-
prising a graduated tube, a cap for closing
5 one end of the tube comprising an air vent
cock, a sieve, and a cap for closing said
sieve, with means for rocking said tube and
adjusting the same in vertical position.

In witness whereof we have signed this
specification in the presence of two witnesses. 10

PAUL KLEMM.
LOUIS SCHOPPER.
